CLAIM

The ornamental design for a reusable produce crate, as shown and described.

DESCRIPTION

FIG. 1 is a perspective view of a reusable produce crate showing my new design;

FIG. 2 is a front elevational view thereof;

FIG. 3 is a rear elevational view thereof;

FIG. 4 is a side elevational view thereof;

FIG. 5 is a top plan view thereof; and,

FIG. 6 is a bottom plan view thereof.

The broken line structure in FIGS. 1-6 showing various elements and features of the reusable produce crate is for environmental purposes only and forms no part of the claimed design.
